UNITED STATES PATENT OFFICE.

AUGUSTUS M. SOSA, OF CINCINNATI, OHIO, ASSIGNOR TO THE AMERICAN TOOL WORKS COMPANY, OF CINCINNATI, OHIO, A CORPORATION OF OHIO.

RELIEVING ATTACHMENT FOR LATHES.

1,081,470.

Specification of Letters Patent. Patented Dec. 16, 1913.

Application filed May 24, 1913. Serial No. 769,753.

To all whom it may concern:

Be it known that I, AUGUSTUS M. Sosa, a citizen of the United States, and residing at Cincinnati, in the county of Hamilton and State of Ohio, have invented a new and Improved Relieving Attachment for Lathes, of which the following specification is a full disclosure.

This invention deals with mechanisms causing a tool alternately to be advanced into and out of the work in a cycle bearing any desired relation to some other component or resultant movement of the work relatively to the tool; and it more especially concerns what is known as a relieving attachment used on machine-tools for the purpose of cutting one or more spiral facets in a revolving piece of work.

The general purpose of this invention is to render available a structurally simple and durable mechanism, preferably in the nature of an attachment, conforming to all or as many as desired of the following capacities; (1) for positively moving a cutting tool toward and into the revolving work always at the same station of its revolution, and then after a definite period, withdrawing it rapidly; (2) for impositively and rapidly moving such tool toward the revolving work and then positively withdrawing it during a cutting operation, all in a reverse cycle to the aforesaid case; (3) for readily effecting a shift from the one to the other mode of operation; (4) for enabling the direction of relieving to be changed at will without affecting the timing or the length of the stroke; (5) for permitting the stroke to be varied in length to any extent desired; (6) for affording any desired periodicity or timing of the reciprocations relative to the movement of the work; (7) for relieving straight, taper or specially contoured work; (8) for progressively retarding or accelerating the cycle in proportion to the general drift or travel of the tool from an inappreciable amount to any desired degree to make cutters having their flutes angling from zero degrees (straight) to any number of degrees corresponding with any given spiral; (9) for permitting the operations to be corresponded with a reversed direction of rotation of the work; and (10) for enabling a wiper-cam and edged follower to be used without being subject to mechanical injury or impair-

ment of its timing adjustment, should the operator momentarily reverse the rotation of the spindle.

An object confined to the particular embodiment here shown is to avoid the use of 60 plunger mechanism extending through the vertical pivot about which the tool post carrier swivels, while yet enabling the carrier to be swiveled to any desired extent without disturbing the correct timing of the 65 reciprocations.

Other objects will be in part obvious from the annexed drawings and in part indicated in connection therewith by the following analysis of this invention. 70

This invention accordingly consists in the features of construction, combination of parts, and in the unique relations of the members and in the relative proportioning and disposition thereof; all as more completely outlined herein. 75

To enable others skilled in the art so fully to comprehend the underlying features thereof that they may embody the same by the numerous modifications in structure and 80 relation contemplated by this invention, drawings depicting a preferred form have been annexed as a part of this disclosure, and in such drawings, like characters of reference denote corresponding parts 85 throughout all the views, of which:—

Figure 1 is a side elevation of a lathe showing this relieving attachment with the tool-post arranged for transverse movements. Fig. 2 is a top plan of the structure 90 shown by Fig. 1 with the tool post, however, turned at right angles to its former position, showing the parts arranged to relieve in parallelism with the guides of the lathe bed, as in making the end-cam shown secured to the spindle. Fig. 3 is a section through line 3—3 of Fig. 1, showing how the tool-post carrier is reciprocated by motion transmitted through the axis of its pivot enabling the tool-post to be adjusted 95 into any angle at which it is desired to relieve the work. Fig. 4 is a plan partially in section along line 4—4 of Fig. 3, with the tool-post and its pivoted base removed, showing the toothed end of the lower half 100 of the transmitting shaft, as well as details of the reciprocating cam. Fig. 5 is a section through line 5—5 of Fig. 3, showing details of the construction enabling the length of the stroke of the reciprocations to be ad- 105 110

usted to any extent desired without interfering with the angle at which the tool post is placed. Fig. 6 is a detail showing the elements connecting the oscillating vertical pivot shaft and the reciprocating tool post.

Continuing now by way of a more detailed description, it may be noted that this invention preferably assumes the form of an attachment applicable to machine tools for the purpose of "relieving" the teeth of the cutters to provide a proper cutting clearance, and it is equally applicable to the formation of cams. It is applicable as well for external as internal, or for right or left, or for straight or irregular relieving. This attachment is shown in this instance applied to a lathe, and it is mounted on the carriage thereof and has a geared connection with the spindle, so that the tool post may be moved in synchronism with the revolutions of the spindle in any multiple or fractional ratio therewith.

The bed of the lathe is indicated by A and comprises the usual conventional features which need not here be specifically described. The means for moving the work through a definite cycle, as for example, in revolving it continuously, here assumes the well known form of a spindle indicated by B, which is mounted in a suitable head-stock 1, and is adapted to be power-driven as by means of the pulleys 2, either directly or through the back gears 3, thus imparting a rotation to the face-plate 4, which carries the work, here instanced as an end-cam 5.

The tool for machining the work is of course mounted on a carriage, here indicated by D, which is adapted to be longitudinally propelled through the agency either of a lead-screw 6 or a splined-shaft 7 in a suitable way, as by means of a gear train leading from the spindle. The foregoing parts are purely conventional in character, and are typical of any machine-tool construction to which my invention may be applied.

The non-vibrating base 8 is mounted on the carriage proper in any suitable way, as by means of a dove-tailed slide-way and, either automatically or by hand wheel 9, may be fed transversely to the guides of the lathe bed to cause the tool to relieve taper work, or special contours. The hand wheel also enables the tool to be adjusted to any desirable position near to or remote from the axis of the spindle when the relieving attachment is used for straight work. By moving the carriage D laterally on the guides, its proximity to the face-plate 4 may also be determined. Extending transversely from the hand-wheel 9 is a shaft 10 that provides screw threads 11, engaging a nut 12 secured to the base 8, so that such base may be adjusted forwardly and rearwardly by hand on the guides 13 provided by the carriage. For enabling automatic transverse

feeds to take place simultaneously with the lateral travel as well as the relieving reciprocations, as by means of a conventional taper bar, the nut 12 is releasably held by a bolt 12' that passes through a slot in the part 8, and thus enables the base to be moved independently of the screw 11. This base 8 may also comprise a portion 14 which supports a revolving cam actuated from the spindle and also mounts the reciprocating element directly operated by the cam. Thus referring to Fig. 4, it will be seen that two journal boxes 15 and 16 rise at the front end of the piece 14, and they constitute journals for a cam shaft 17. It is noteworthy that this shaft is removable so as to enable the cam to be reversed in position thereon and, to that end, a cap 18 is secured in the end of the journal box 16 and by means of a spring 19 maintains a clutch-sleeve 20 in engagement with the teeth on the adjacent side of the cam or wiper 21 to drive the same positively in one direction, but inoperative to drive it in the other direction. The clutch sleeve 20 is splined to the shaft 17 which latter may be removed by knocking out the taper pin 18' and taking the retaining collar off the end of the shaft. The cam 21, which is loose on the shaft 17, may now be reversed in position on said shaft. It is to be noted that this withdrawal of the shaft will not cause a removal of the sleeve 20 as it will still be retained by the flange 20'.

The cam shaft 17 is positively actuated in all positions of the carriage, or the parts mounted thereon, by some suitable means, as for example, through the motion-transmitting shaft C comprising a splined shaft 22, journaled in an arm 23, (against axial movement) and extends forwardly through the gear 24 which is driven from the spindle gear 25 by means of suitable intermediates 26 and 27, adapted to be changed to vary the timing of the reciprocations of the tool post relative to the rotation of the spindle. By virtue of a splined connection between the shaft 22 and gear 24 (forming an extensible joint), the motion is transmitted irrespective of any movements of the carriage D, thus enabling the work to be relieved while said carriage is being propelled longitudinally, and also by reason of the universal joint connection between the bracket 23 and the bearing 15, the tool post may be adjusted transversely of the lathe bed. This splined shaft will, of course, determine the extent of retardation or acceleration of the relieving cycle relative to the revolutions of the work, thus determining whether the flutes relieved are to be straight or spiral. Thus, when the spline in the shaft 22 is straight, then the flutes will be equally straight, since the acceleration will be inappreciable, and it will be quite obvious that as the spline departs from a straight line, so also will the flutes

become correspondingly spiraled. Or, by using a fractional or "hunting" ratio for the gear train to 24, a similar effect may be obtained with a straight spline.

5 Pivoted to the non-vibrating part 14 is a support 28, on which the tool-post carrier is in turn slidably mounted. This intermediate non-vibrating support or turret 28 is maintained at all times in exact concentricity with the non-vibrating member 14 by means of a pivot sleeve 29 and, through this sleeve, the motion for vibrating the tool-post support is transmitted, as will be described. This intermediate support or turret 28 may 10 be angled and locked in any position by means of clamp-bolts 30 thereby determining the line of direction in which the tool is to reciprocate in its relieving operation.

20 The tool itself is mounted on a conventional post 31, which is carried by the slideable carrier 32, which has opposite guide rails 33 and 34, so as to provide ample room for the movement of the parts projecting through the axis of the turret 28. The 25 means enabling a vibrating or reciprocating motion to be transmitted to the tool-post carrier 32 will now be described.

30 Slidably mounted in the non-vibrating base or supporting member 14 is a plunger 35, which is normally urged into one extreme position of its stroke by means of an expansible spring 36 that bears at one end on a stud 37 rigid with the part 14, and at its other end it bears against the head 35 of a bolt 38 rigid with the vibrating plunger 35, as appears more clearly from Fig. 3. An interposed shock-absorbing washer 39 of leather may be used. The plunger is actuated at its forward end 40 by means of a 40 shiftable shoe or follower 41, secured by means of a screw 42 in a vertical position to correspond with anti-clockwise rotations of the actuating wiper cam 21 and, also capable of being interchanged in position to 45 correspond with clockwise rotation of the cam 21, by being screwed in a horizontal position as indicated by the dotted lines on Fig. 3. The expansible spring 36 maintains this shoe 41 in contact with the surface of the tripping cam 21 so that, as this cam rotates, the plunger 35 will be correspondingly reciprocated. It will be observed that the cam is of the abruptly acting type (technically a wiper) and the follower has 55 an acute edge, so distinguished from a roller. This enables more precise actions to take place, and yet, by reason of the peculiar ratchet-like mounting of the cam, no breakage will occur should the lathe be 60 turned backwardly by hand. It is also noteworthy that the clutch teeth connecting the cam to the actuating sleeve 20 are symmetrically related to the cam-facets so that regardless of the number of "slip-backs" of 65 the cam by a reverse rotation of the spindle,

the correct timing will always be maintained during the forward rotation.

A two-part shaft 43, having its two portions connected by a dog-clutch, carries a rocker-arm 44 on its lower end, and this arm is designed to engage the front and rear walls 45 of a slot or seat provided by the plunger 35, so that the shaft 43 will be rocked in synchronism with the reciprocations of the plunger 35 and to an extent 75 corresponding with the stroke of said plunger.

The upper portion of the shaft 43 is connected with an element 46 providing a slide-way 46' in which is confined and freely 80 slides a shoe 47, to which by means of a pin 48 is pivoted a nut 48' through which is screw threaded a hand-screw 49 operated by a hand wheel 50, and mounted on the tool-post carrier 32 so that by turning the 85 hand screw 49 the initial position of the support 32 relative to the non-reciprocating part 28 may be determined.

It will be perceived that if the shaft 43 rocks through any given angle, then will 90 the length of the stroke of the tool post support 32 depend upon the eccentricity of the axis of the pivot pin of the nut 48 with respect to the axis of the shaft 43. In other words, should the axis of the shoe 47 be 95 concentric with that of the rock shaft 43, then there will be no reciprocation of the tool-post support 32 and, as the two axes are farther and farther separated, so also will the length of the stroke of the tool be 100 progressively increased. This invention proposes a means for accomplishing this irrespective of any angle at which the tool post carrier may be set and without requiring 105 complexity of construction.

The length of the stroke may be very easily 110 varied with accuracy and precision by the mechanism herein proposed, through the assistance of a scale enabling the desired length to be attained without approximation by trials. Instead of being secured directly to the tool carrier 32, the head screw 49 is mounted in a cradle 51 which is itself 115 adjustable laterally, but not longitudinal of the support 32. Thus, the cradle 51, provides wings 52 and 53 which bear against the end of the support 32, and are preferably slotted to reclamping bolts 54 and 55, enabling the cradle to be rigidly fixed in any one of its adjustable positions. To aid in 120 obtaining a fine adjustment, a screw 56 is secured to the cradle and projects into screw engagement with a micrometer nut 57 that is journaled in the side wall of the tool support 32. By turning this micrometer 125 nut the cradle may be shifted laterally, thus varying the distance between the axes of the rock shaft 43 and the actuating pivot of the tool post. As shown by Fig. 2, the upper 130 surface of the end of the cradle 51 is gradu-

ated, and coöperating graduations 58 may be provided on the upper surface of the adjacent member 32. A small handle 59 operating a set screw, enables the feed screw 49 to be locked against rotation during the operating of the relieving mechanism so that the adjustment may not be shaken loose or disturbed.

Another notable capacity of this structure is that it enables the tool to be jumped by spring action toward the work followed by a deliberate positive motion retreat, or conversely, it enables the tool to be deliberately and positively advanced toward the work followed by the backward jump under spring action. This dual capacity is of advantage where different classes of work are to be relieved. Thus, it enables either right or left hand taps to be relieved without reversing the direction of rotation of the spindle; for, in the case of a right-hand tap, the tool will be jumped quickly into the rear of the tap-blade and then withdrawn slowly while relieving, leaving the tap-blade at its cutting edge. In the case of a left-hand tap, assuming the direction of the spindle to be unchanged, the tool will start at the cutting edge of the tap-blade and slowly advance into the work, and then ultimately snap back into position opposite the cutting edge of the next blade, and so on. For internal relieving, either right or left-handed, a similar adaptability prevails, and in like manner, the tool may be effectively mounted on either side of the axis of the work, and used for either clock-wise or anti-clockwise rotations of the work.

To reverse the sequence of the cycle of the relieving tool, so that the positive movements take place while the tool is advancing instead of returning, or conversely, it is only necessary to shift the cradle laterally on the tool-post carrier past the zero point, so that the pin actuating the nut will lie on the opposite side of the axis of the vertical rock-shaft. The slotted head of said rock-shaft extends in opposite directions to enable this to be done, and as the opposite arms of such head move in opposite directions with respect to the cradle, the latter will have its cycle of operations reversed by thus shifting the actuating pin, so that its positive and impositive strokes will follow in reverse order.

It may here be observed that this apparatus is so designed that it may be used in the ordinary way, whenever it is desired to operate the same by hand, and without dismounting its other adjustments. Thus, by shifting the cradle 51 to its zero or neutral point, its actuating pivot will become coaxial with the rock shaft 43, and no reciprocation will result, even though such rock shaft be in motion, and any hand-tooling may then be done to the extent desired.

As described thus far, no mention has been made of the provision for enabling the direction of the reciprocating tool carrier to be changed without disturbing the timing of the strokes, *i. e.* altering the points in the cycle at which such strokes begin and end. By the means herein disclosed however, the relieving may be done in any direction while yet enabling the strokes to begin always at the same station in the cycle of movements of the work actuated by the spindle. For instance, suppose it is desired merely to change the direction of the stroke, but otherwise maintain the same adjustment so as not to disturb the timing. To do this, the attendant will merely loosen bolts 30 and lift up the swivel-block 28 until the upper half of the rock shaft 43 is disengaged from the lower half; this being done only when the plunger 35 is at the end of its stroke to the right. In this position, the head of the shaft containing the slide-way 46 will be against the pin shown in Fig. 5 and indicated by 60. When the upper half of shaft 43 is detached from its lower half, the parts will still be maintained in this position, by reason of the spring-pressed plunger 61. The tool-post carrier is now brought to the desired angle and then lowered until the teeth engage to lock the upper and lower halves of the rock shaft 43 together, whereupon bolts 30 will be tightened, and the parts are now in proper adjustment for further operation; but at the same time maintaining the timing in the cycle of the reciprocations.

It will thus be seen that this invention is well adapted to achieve the objects enumerated in the foregoing while yet possessing great structural simplicity and a capacity for meeting all requirements that would ordinarily arise in connection with the use of a relieving attachment. Although the attachment consists of but few parts, it will accomplish all the work and meet all the requirements of much more complicated and costly structures.

Without further elaboration, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed my invention, I claim as new and desire to secure by Letters Patent of the United States:—

1. A relieving mechanism of the nature disclosed combining a swivel support, a tool post carrier adapted to be reciprocated

thereon in various directions, mechanism for reciprocating said carrier in a predetermined cycle of movements, a power transmitting shaft for actuating said mechanism, and adjusting means coöperating with said mechanism for enabling the cycle of movements to be reversed in any direction of reciprocation of said carrier.

2. A relieving mechanism of the nature disclosed combining a swivel support, a tool post carrier mounted thereon, an actuating member arranged coaxially with said support, means for moving said member in a predetermined cycle, and means connecting said member with said carrier whereby the latter may be reciprocated either in direct or reverse relation with said member.

3. A relieving mechanism of the nature disclosed combining a swivel support, a tool carrier slidably mounted thereon, an actuating shaft coaxially arranged with said support, means for actuating said shaft in a constant cycle, and an adjustable connection between said shaft and said carrier whereby the latter may be reciprocated in strokes of any predetermined length, and whereby the cycle of said reciprocations may be reversed.

4. A relieving mechanism of the nature disclosed combining a swivel support, a tool carrier reciprocating thereon, a rock-shaft mounted on said support, means for rocking said shaft at a constant rate, and an adjustable connection between said shaft and said carrier adapted to be eccentrically related to said shaft on either side of the axis thereof and at any desired distance from said axis.

5. A relieving mechanism of the nature disclosed combining a support, a tool carrier slidably mounted thereon, a rock-shaft extending vertically through said support, means for rocking said shaft, and a slotted cross-arm fixed to the upper end of said rock-shaft having a slot crossing the axis thereof, and a member laterally movable on said carrier having a pin entering said slot, said member being adjustable to bring the axis of said pin to either side of the axis of said shaft.

6. A relieving mechanism of the nature disclosed combining a supporting member, a tool carrier adapted to reciprocate thereon, a stop limiting the impositive movement of said tool carrier, a spring normally urging said tool carrier in the direction limited by said stop, a wiper adapted to positively move said tool carrier against the resistance of said spring, a shaft on which said wiper is mounted, and a spring-pressed ratchet-clutch adapted to transmit motion from said shaft to said wiper in one direction of rotation and unadapted to drive it in the opposite direction of rotation.

7. A relieving mechanism of the nature disclosed combining a longitudinally movable carriage, a member slidably mounted

thereon to be moved transversely thereto, a cam-shaft journaled on said member, a swivel block pivoted on said member, a tool carrier slidably mounted on said swivel block, connections receiving intermittent motion directly from said cam-shaft and extending coaxially with said swivel block adapted to reciprocate said tool carrier, and a universal shaft journaled at one end on said carriage and connected with said cam-shaft.

8. A relieving mechanism of the nature disclosed combining a work-revolving spindle, a guide-bed parallel with the spindle axis, a carriage slideable on said guide-bed, a carriage-propelling train geared to said spindle, a member adjustable transversely on said carriage, an actuated part journaled on said member in parallelism with said guide-bed, a transmission embodying a universal shaft enabling said part to be actuated from said spindle, a swivel-block pivoted to said member, a tool carrier slidably mounted on said swivel-block, and motion transmitting means extending transversely from said actuated part through the axis of said swivel-block to said carrier, and adapted to impart a reciprocating motion thereto.

9. A relieving mechanism of the nature disclosed combining a work-revolving spindle, a guide-bed parallel with the spindle axis, a carriage slideable on said guide-bed, a carriage-propelling train geared to said spindle, a member adjustable transversely on said carriage, a shaft journaled on said member in parallelism with said guide-bed, an actuating cam mounted on said shaft, a transmission for actuating said shaft from said spindle, a swivel-block pivoted to said member, a tool-carrier slidably mounted on said swivel-block, and means intermittently actuated by and extending from said cam through the axis of said swivel block to said carrier, and adapted to impart a reciprocating motion thereto.

10. A relieving mechanism of the nature disclosed combining a work-revolving spindle, a guide-bed parallel with the spindle axis, a carriage slideable on said guide-bed, a carriage-propelling train geared to said spindle, a member slideable transversely on said carriage, a horizontal shaft journaled on said member, a cam having a ratchet-mounting on said shaft enabling it to be positively driven in one direction only, a transmission for actuating said shaft, a swivel-block pivoted to said member, a vertical shaft coaxial with said swivel-block and intermittently actuated from said cam, and a tool carrier slidably mounted on said swivel-block and adapted to be reciprocated by said vertical shaft.

11. A relieving mechanism of the nature disclosed combining a tool carrier adapted to reciprocate in a predetermined direction,

an actuating shaft arranged transversely to the direction of reciprocation of said carrier, a positive connection between said shaft and said carrier enabling said shaft to reciprocate said carrier positively during both its forward and return strokes, and means for intermittently moving said shaft by alternating positive and impositive movements.

12. A relieving mechanism of the nature disclosed combining a tool carrier adapted to reciprocate in a predetermined direction, an actuating shaft arranged transversely to the direction of reciprocation of said carrier, a positive connection between said shaft and said carrier enabling said shaft to reciprocate said carrier positively during both its forward and return strokes, a cam operative intermittently and positively to actuate said shaft, and a spring effective to alternate with said cam in impositively actuating said shaft.

13. A relieving mechanism of the nature disclosed combining a tool carrier adapted to reciprocate in a predetermined direction, an actuating shaft arranged transversely to the direction of reciprocation of said carrier, a positive connection between said shaft and said carrier enabling said shaft to reciprocate said carrier positively during both its forward and return strokes, a supporting member, a swivel-block thereon arranged coaxially with said shaft and supporting said carrier, a spring-pressed reciprocating element mounted on said member and coacting with said shaft, and a cam journaled on said member and operative to reciprocate said element against the resistance of said spring.

14. A relieving mechanism of the nature disclosed combining a supporting member, a tool carrier slidably mounted to be reciprocated on said member, an element mounted to oscillate about an axis extending transversely to the direction of reciprocation of said carrier, said oscillating element providing a guide-way extending transversely both to the direction of said reciprocation and to said axis and across the latter, an interponent for transmitting motion from said element to said carrier and adjustably mounted on one of the same, said interponent coöperating with said guide-way and adapted to be located at either side of said axis to enable a given stroke of said element to impart a forward or backward stroke to said tool carrier, and means mounted on one of said last two mentioned parts for adjusting the position of said interponent relatively to said axis.

15. A relieving mechanism of the nature disclosed combining a lower supporting member, an intermediate block swiveled to said member, an upper tool carrier slidably mounted on said block and adapted to be reciprocated thereon, an actuating shaft extending vertically and coaxially through

said intermediate block, a part movably mounted on the said lower supporting member and connected with said shaft periodically to move the same relatively to said block, an oscillating element arranged at the upper end of said shaft and adapted to be oscillated thereby about a given axis, said element having a guide-way extended to opposite sides of said axis, and an interponent adjustable along said guide-way to either side of said axis and coöperating with said tool carrier to reciprocate the same in a direct or reverse cycle.

16. A relieving mechanism of the nature disclosed combining a lower supporting member, an intermediate block swiveled thereto, an upper tool carrier slidably mounted to be reciprocated on said block, an element mounted to oscillate about a given axis extending transversely to the direction of reciprocation of said carrier, said oscillating element providing a guide-way extending transversely to said direction of reciprocation and also extending transversely to and across said axis, an interponent movable with said element and coöperating with said guide-way and adjustable therealong to occupy a position at either side of said axis, said interponent also coöperating with said carrier to actuate the same effectively from either side of said axis, and a shaft arranged coaxially with said block and movable periodically to oscillate said element.

17. A relieving mechanism of the nature disclosed combining a lower supporting member, an intermediate block swiveled thereto, an upper tool carrier slidably mounted to be reciprocated on said block, an element mounted to oscillate about a given axis extending transversely to the direction of reciprocation of said carrier, said oscillating element providing a guide-way extending transversely to said direction of reciprocation and also extending transversely to and across said axis, an interponent movable with said element and coöperating with said guide-way and adjustable therealong to occupy a position at either side of said axis, said interponent also coöperating with said carrier to actuate the same effectively from either side of said axis, a vertical shaft extending coaxially through said block and movable to oscillate said element, and a cam-shaft journaled on said lower supporting member and enabled periodically to actuate said shaft.

18. A relieving mechanism of the nature disclosed combining a supporting member, a tool carrier slidably mounted to be reciprocated on said member, an element mounted to oscillate about an axis extending transversely to the direction of reciprocation of said carrier, said oscillating element providing a guide-way extending transversely both to the direction of said reciprocation and to said axis and across the latter, an

- interponent for transmitting motion from said element to said carrier and adjustably mounted on one of the same, said interponent coöperating with said guide-way and adapted to be located at either side of said axis to enable a given stroke of said element to impart a forward or backward stroke to said tool carrier, means mounted on one of said last two mentioned parts for adjusting the position of said interponent relatively to said axis, a shaft extending through said supporting members for operating said oscillating element, and means for periodically moving said shaft.
- 15 19. A relieving mechanism of the nature disclosed combining a lower supporting member, an intermediate block swiveled thereto, an upper tool carrier slidably mounted to be reciprocated on said block, an element mounted to oscillate about a given axis extending transversely to the direction of reciprocation of said carrier, said oscillating element providing a guide-way extending transversely to said direction of reciprocation and also extending transversely to and across said axis, an interponent movable with said element and co-operating with said guide-way and adjustable therealong to occupy a position at either side of said axis, said interponent also co-operating with said carrier to actuate the same effectively from either side of said axis to enable a given stroke of said element to impart a forward or a backward stroke to said tool carrier, a vertical shaft extending coaxially through said block and movable to oscillate said element, and a horizontal shaft journaled on said lower supporting member, and a cam moved by said shaft and enabled periodically to actuate said vertical shaft.
- 20 20. A relieving mechanism of the nature disclosed combining a non-reciprocating member, an overlying non-reciprocating member swiveled thereto, a reciprocating tool carrier slidably mounted on said overlying member, a rock-shaft coaxial with the swiveled member, means carried by the underlying member for rocking said shaft, and means intervening between said carrier and the upper end of said rock-shaft for enabling the latter to reciprocate the other.
- 25 21. A relieving mechanism of the nature disclosed combining a non-reciprocating lower member, a superposed member swiveled thereto, an upper member slidably mounted on said superposed member, a shaft coaxial with said superposed member, means carried by said lower member adapted to turn said shaft, means enabling the upper end of said shaft to reciprocate the upper member while turning, and means for effecting an angular adjustment between said two means in exact correspondence with a predetermining angular adjustment of the swiveled member with relation to its supporting member.
- 30 22. A relieving mechanism of the nature disclosed combining a lower non-reciprocating member, an upper reciprocating member, an intervening member swiveled to the lower member and slidably connected to the upper member, a two-part shaft extending from the upper to the lower member in coaxial relation with the intervening member, the sections of said shaft being adapted to be non-rotatably connected, means mounted on the lower member for turning the shaft, and means enabling the upper end of the shaft to reciprocate the upper member.
- 35 23. A relieving mechanism of the nature disclosed combining a lower member, an intermediate member swiveled thereto, an upper member slidably mounted on the intermediate member, a cam mounted on the lower member, a shaft extending from the lower to the upper member coaxially through the intermediate member, a reciprocating connection between the cam and the lower end of said shaft whereby it may be rocked about its axis, and means intervening between the upper end of the shaft and the upper member for enabling the shaft to reciprocate said member.
- 40 24. A relieving mechanism of the nature disclosed combining a lower member, an intermediate member, an upper member slidably mounted on the intermediate member, a shaft extending from the lower to the upper member and adapted to be rotated, a sliding-pin and slot connection between the upper end of said shaft and said upper member, and means embodied in said connection for enabling the normal eccentricity or throw of the same to be varied.
- 45 25. A relieving mechanism of the nature disclosed combining a tool-post carrier, a cradle laterally adjustable thereon, a feed-screw journaled in said cradle, a nut longitudinally movable on feed-screw and having a depending pin, a lower member on which said tool-carrier is supported, a vertical shaft journaled in said lower member and terminating in a slotted head receiving said pin, whereby said tool-carrier may be reciprocated as said shaft is rotated, and means for turning said shaft.
- 50 26. A relieving attachment of the nature disclosed combining a lower member, an intermediate member swiveled thereto, an upper tool-carrier slidably mounted on said intermediate member, a shaft vertically journaled in the intermediate member and terminated in an upper slotted end, a part having a pin engaged by said slot and adapted to be shifted on said upper member laterally to its sliding direction to enable the throw of said pin to be varied, said part being also adapted to be shifted relative to

said upper member along the line of reciprocation thereof, whereby the normal position of said upper member on said intermediate member may be varied, and means 5 mounted on said lower member for rotating said shaft.

27. A relieving mechanism of the nature disclosed combining a longitudinally movable carriage, a longitudinally extending shaft having one end journaled on said carriage and movable axially therewith, a cam mounted on said shaft, a member adapted to be reciprocated by said cam transversely to the travel of the carriage, an intermediate

member swiveled to the carriage, a rock- 15 shaft arranged coaxially with said intermediate member and adapted to be rocked by said reciprocating part, and a tool carrier slidably mounted on said intermediate member and adapted to be reciprocated by 20 said shaft.

In witness whereof, I hereunto subscribe my name, as attested by the two subscribing witnesses.

AUGUSTUS M. SOSA.
